CONVERTIBLE LOUNGE

Martin Fox, Chicago, Ill., assignor to The Seng Company, a corporation of Illinois

Application September 26, 1945, Serial No. 618,715

4 Claims. (Cl. 5—59)

1

This invention relates to convertible lounges adapted to be used as a bed or a couch.

The primary object of the invention is to provide an extremely simple convertible bed which, when changed to a couch, will automatically incline the seat portion backwardly and downwardly so as to be more comfortable. When converted to a bed, the bed spring is brought to horizontal position and the pillow supporting the back bar is swung forwardly out of the way.

A further object of the invention is to provide a strong and durable mounting for the pivotal legs which are operated automatically by a connection with the back bar.

The invention is illustrated in a preferred embodiment in the accompanying drawings, in which—

Figure 1 is a plan view of the bed frame and mechanism with the box spring and mattress removed; Fig. 2, an end elevational view of the device in bed position; and Fig. 3, an end elevational view showing the device converted into a couch.

In the embodiment illustrated, a bed frame 4 is formed of the usual metal angle bar members and has its front side supported by stationary legs 6. Each end of the frame is provided with a fixed depending supporting plate 7, which is secured in position by rivets 8. The plates are provided with arcuate slots 9 through which pivot members 10 extend. Rear legs 11 are pivotally mounted on the frame, as indicated at 12 and may be provided at the lower end with a roller or caster 13.

The frame is also provided at each end with a plate 14 which is riveted to the bed frame, as indicated at 15, and has its top portion turned inwardly to form a stop 16. A pillow-supporting back rest is formed from a tubular bar 17 whose end portions are turned downwardly and are pivotally supported on the plate 14, as indicated at 18. Preferably, the ends of the bar have a slightly bent portion which forms a rigid elbow, as indicated at 19. A pitman 20 is provided at each end of the bed and makes a pivotal connection at the lower end of the back bar, as indicated at 21, and the other end is connected to an intermediate portion of the leg 11 by the pivot 10, which extends through the arcuate slot 9, said leg and said pitman being on opposite sides of the plate 7.

2

It will be understood that in sitting position the bar is turned up to the position indicated in Fig. 3, and will support pillows, indicated at 22, when the device is used as a seat. In this position the back bar rests against the stops 16 and the legs 11 are swung back so as to lower the rear portion of the bed frame. The plate 7 restrains the legs against longitudinal movement with respect to the bed frame, and rearward movement of the legs is limited by the slots 9 and the stops 16. To transform the couch to a bed, it is merely necessary to swing the bar 17 forwardly to the floor, as indicated in Fig. 2.

The foregoing detailed description is given for clearness of understanding only, and no unnecessary limitations should be understood therefrom, for some modifications will be obvious to those skilled in the art.

I claim:

- 20 1. A convertible lounge comprising: a bed frame provided with a pair of front legs and a pair of rear legs, one pair of said legs being pivotally mounted on said frame for forward and rearward movement to raise or lower one side of the bed frame; a U-shaped back bar having its ends pivotally connected to the ends of said frame near its center portion; and a pair of links connecting said pivotal legs to said back bar so that the legs will support the bed frame in horizontal position when the bar is swung to its foremost position and will incline said bed frame downwardly and rearwardly when the bar is raised upwardly to a position where it will form a back support for pillows in upright position.
- 25 2. A lounge as specified in claim 1, in which guide plates are mounted on the bed frame adjacent to pivotal legs to restrain endwise movement, said plates having arcuate slots to receive
- 30 30 pivot pins connecting said legs to the links and limit the oscillation of the legs.
- 35 3. A lounge as specified in claim 1, in which the rear legs are pivotally mounted and the front legs are stationary.
- 40 45 4. A lounge as specified in claim 1, in which supporting plates are provided on the ends of the bed frame to afford pivots for the back bar, and said supporting plates are each provided with an integrally formed stop to limit the rearward travel of said back bar.

MARTIN FOX.
